UNITED STATES PATENT OFFICE.

MEYER L. ROBBINS, OF NEW YORK, N. Y.

DESIGN FOR AN EXPANSIBLE CHAIN.

43,235.

Specification for Design.

Patented Nov. 5, 1912.

Application filed September 6, 1912. Serial No. 719,035. Term of patent 7 years.

To all whom it may concern:

Be it known that I, MEYER L. ROBBINS, a citizen of the United States, and a resident of New York, borough of Manhattan, in the county of New York and State of New York, have invented a certain new, original, and ornamental Design for Expansible Chains, of which the following is a specification.

Figure 1 is a plan view of a portion of

expansible chain having my design applied thereto; Fig. 2 is a side or edge view thereof.

I claim:

The ornamental design for an expansible chain as shown.

MEYER L. ROBBINS.

Witnesses:

ARMAND MANTONE,

ALMA ROLLER.
